UNITED STATES PATENT OFFICE.

HELEN MARTHA BUCK, OF NEW YORK, N. Y., ASSIGNOR TO THE CAMP FIRE GIRLS, INC., A CORPORATION OF NEW YORK.

DESIGN FOR A WOMAN'S OR MISS'S COSTUME.

55,244.

Specification for Design.

Patented May 25, 1920.

Application filed June 30, 1917. Serial No. 178,040. Term of patent 3½ years.

To all whom it may concern:

Be it known that I, HELEN MARTHA BUCK, a citizen of the United States, residing in the city, county, and State of New York, have invented a new, original, and ornamental Design for Women's or Misses' Costumes, of which the following is a specification, reference being had to the accompanying drawing, forming a part thereof, and which shows a costume made according to my design in front elevation.

What I claim is:

The design for a woman's or miss's costume shown in the accompanying drawing.

HELEN MARTHA BUCK.
